UNITED STATES PATENT OFFICE.

BENNETT H. LIGHT, OF AVON, PENNSYLVANIA.

RAILWAY-TIE.

1,164,536.

Specification of Letters Patent. Patented Dec. 14, 1915.

Application filed February 20, 1915. Serial No. 9,676.

To all whom it may concern:

Be it known that I, BENNETT H. LIGHT, a citizen of the United States, residing at Avon, in the county of Lebanon and State 5 of Pennsylvania, have invented new and useful Improvements in Railway-Ties, of which the following is a specification.

The present invention relates to improvements in ties for supporting railway rails, 10 and the primary object of the invention is to construct ties which shall comprise each a pair of I-beams that are pivotally or hingedly connected at the meeting ends of one of the horizontal portions of each of said 15 I-beams, the ties being arranged to have their pivoted hinged members alternate so that the pivot or hinge of one tie will be arranged upon the upper face of the said tie and the pivot or hinge of the next tie will be arranged upon the lower face of the said tie whereby a certain and desired amount of 20 resiliency is afforded to the ties and to the rails supported by the ties, and also whereby the roadbed may be effectively tamped 25 around the ties.

Another object of the invention is to provide ties each comprising two I-beam sections hinged at their upper or lower faces and to provide the same with means where- 30 by rails may be secured thereon.

With the above and other objects in view, the improvement resides in the construction, combination and arrangement of parts set forth in the following specification and fall- 35 ing within the scope of the appended claim.

In the drawing: Figure 1 is a top plan view of a tie constructed in accordance with my invention and showing the means for supporting rails thereon, Fig. 2 is a sec- 40 tional view approximately on the line 2—2 of Fig. 1, and Fig. 3 is an end view looking toward one of the ties.

In the drawing, 1—1 designate two rails of the ordinary construction and 2—3 the 45 ties upon which the rails are supported.

Each of these ties preferably comprises a channelled member or I-beam, the upper and lower portions 4 and 5 respectively being horizontally straight so that the roadbed 50 may be received within the channelled sides. The upper portions 4 of certain of the ties

are formed with loops or butts 6, the same being arranged at the opposite sides of their connecting member 7, and the said loops of one of said sections are adapted to receive 55 a central or intermediate loop 8 of the second or co-acting tie section, while a pin 9 passes through the said loops or butts.

One of the sections of the second or intermediate tie, indicated by the numeral 3 60 is provided upon its lower flanged portion 5, at the opposite sides of its connecting member 7 with loops forming butts 10, while the second section of the tie is centrally provided with a loop or butt 11, the said loops 65 or butts being provided with a pivotal connection 12.

The flange members 4 of each of the tie sections 2 and 3 at the opposite sides of its web or connecting member 7 are provided 70 with openings through which pass headed members 13, the heads of said members engaging with the flanges of the rails 1, while nuts 14 engage with the threaded shank of the said members 13 to retain the same in 75 locked position upon the ties, as clearly illustrated in the drawing.

From the above description, taken in connection with the accompanying drawing, the simplicity of the device, as well as the advantages thereof will, it is thought, be perfectly apparent to those skilled in the art to which such invention appertains without further detailed description.

Having thus described the invention, what 85 I claim is:

Ties comprising I-beams including each a pair of sections having their horizontal flanges at their meeting ends pivotally connected, said ties being arranged in the roadbed and having their pivots alternate so that the pivot of one of the ties will be arranged upon the upper face of the said tie and the pivot of the next tie will be arranged upon the lower face of the said tie. 95

In testimony whereof I affix my signature in presence of two witnesses.

BENNETT H. LIGHT.

Witnesses:

R. L. MILLER,
CHARLES WALLACE STEFFY.
